By Attorney

UNITED STATES PATENT OFFICE.

JOSEPH P. HOLLAND, OF KEY WEST, FLORIDA.

CHAIR-SEAT.

1,345,187.

Specification of Letters Patent. Patented June 29, 1920.

Application filed December 9, 1919. Serial No. 343,455.

To all whom it may concern:

Be it known that I, JOSEPH P. HOLLAND, a citizen of the United States, residing at Key West, in the county of Monroe and State of Florida, have invented certain new and useful Improvements in Chair-Seats; and I do hereby declare the following to be a full, clear, and exact description of the invention, such as will enable others skilled in the art to which it appertains to make and use the same.

The invention relates to new and useful improvements in seats for dentistry, barber, and like chairs and has for its primary object the provision of a plurality of reversible covered panels operated in unison by a means so that a clean surface can be presented whenever one surface becomes soiled or worn or the device can be reversed after each occupant, so as to render the device highly sanitary.

Another object of this invention is the provision of means for locking the panels in seat forming position, thereby preventing rotation or disarrangement of the panels during the use of the device or when occupied.

Another object of this invention is the provision of a chair seat of the above stated character which shall be simple, durable and efficient, and which may be manufactured and sold at a comparatively low cost.

With these and other objects in view as will become more apparent as the description proceeds, the invention consists in certain novel features of construction, combination, and arrangement of parts as will be herein-after more fully described and claimed.

For a complete understanding of my invention, reference is to be had to the following description and accompanying drawings, in which:

Figure 1 is a plan view of the chair seat constructed in accordance with my invention,

Fig. 2 is a longitudinal sectional view of the same,

Fig. 3 is a transverse sectional view illustrating the shape of the panels.

Fig. 4 is a front elevation of a locking member.

Referring in detail to the drawing, the numeral 1 indicates as an entirety a reversible seat to be used in connection with dentistry, barber, doctor, and like chairs and as my invention resides in the seat, the other

portions of the chair are not shown. The seat includes a frame 2 consisting of end channel members 3 and 4 connected by longitudinally extending bars 5. The open ends 60 of the channel members 3 are disposed uppermost and have their inner walls provided with spaced openings 6 to rotatably receive supporting bars 7 to which are secured elongated panels 8 the faces of which are 65 covered with suitable upholstering 9. The upholstering 9 may have linen covers and the like secured thereon if desired. The rear ends of the bars 7 have secured thereto pinions 10 located within the rear channel member 4 and mesh with pinions 11 secured to an operating shaft 12. The operating shaft 12 is journaled in the rear channel member 4 or the end wall thereof and one end of said operating shaft 12 projects beyond the 75 frame 2 and is bent to form an operating handle 13 whereby on turning the handle, the panels will be compelled to rotate in unison for the purpose of presenting another face to the seat when one face has become 80 soiled or worn. A cover 14 is removably secured to the rear channel member 4 and is adapted to conceal and protect the pinions and operating shaft therein.

The forward ends of the supporting bars 85 7 project beyond the inner wall of the front channel member 3 and are provided with squared faces 15 which are adapted to contact with the walls of slots 16 formed in the upper edge of a locking strip 17. The locking strip 17 is pivotally mounted in the front channel member 3 as illustrated at 18 and has secured thereto a spring 19 which is in turn connected to the channel member 3 for normally holding the locking strip 17 90 so that the supporting bars will be held against accidental rotation, thereby holding the panels horizontally to form an even seat. A handle 20 is formed on one end of the locking strip 17 and projects outwardly of the 100 frame 2 so that said locking strip can be swung away from engagement with the ends 15 of the supporting bars 7 when it is desired to reverse the panels.

A cover 21 is removably secured to the 105 front channel member 3 for the purpose of concealing the locking strip 17 and the forward ends of the supporting bars and also is adapted to give a neat appearance to the front edge of the seat.

While I have shown and described the preferred embodiment of my invention, it

will be understood that minor changes in construction, combination, and arrangement of parts may be made without departing from the spirit and scope of the invention 5 as claimed.

Having thus described my invention, what I claim is:—

A chair seat comprising front and rear channel members, bars connecting said channel members, supporting bars journaled to the inner walls of the channel members, panels secured to the supporting bars, an operating shaft journaled in the rear channel member, means connecting the supporting bars

to the operating shaft, upholstering secured 15 to the panels, a tension and pivotally mounted locking plate pivoted in the front channel member and having notches to receive the ends of the supporting bars for holding them against accidental rotation, and removable covers closing the upper ends of the channel members.

In testimony whereof I affix my signature in presence of two witnesses.

JOSEPH P. HOLLAND.

Witnesses:

J. FUHRBAM,
THOS. K. WARREN.
